UNITED STATES PATENT OFFICE.

DOUGLAS HENRY STOKES, OF CREMORNE, NEAR SYDNEY, NEW SOUTH WALES,
AUSTRALIA.

DESIGN FOR A CLOSED CASING FOR REFRIGERATING-MACHINES.

49,808.

Specification for Design.

Patented Oct. 24, 1916.

Application filed July 19, 1916. Serial No. 110,235. Term of patent 7 years.

To all whom it may concern:

Be it known that I, DOUGLAS HENRY STOKES, a subject of the King of Great Britain and Ireland, residing at Murdoch street, Cremorne, near Sydney, New South Wales, Australia, have invented a new, original, and ornamental Design for a Closed Casing for Refrigerating-Machines, of which the following is a specification, reference being had to the accompanying drawing, forming part thereof.

The figure is a perspective view of a closed

casing for a refrigerating-machine showing my new design.

I claim:

The ornamental design for a closed casing for refrigerating machine, as shown.

Signed at Sydney, New South Wales, Australia, this 19th day of June, 1916, in the presence of two subscribing witnesses.

DOUGLAS HENRY STOKES.
